UNITED STATES PATENT OFFICE.

RAY B. WHITMAN, OF BRIDGEPORT, CONNECTICUT, ASSIGNOR TO COLUMBIA PHONOGRAPH COMPANY, INCORPORATED, OF BRIDGEPORT, CONNECTICUT, A CORPORATION OF NEW YORK.

TURNTABLE FOR PHONOGRAHS.

Application filed December 19, 1921. Serial No. 523,361.

To all whom it may concern:

Be it known that I, RAY B. WHITMAN, a citizen of the United States, and a resident of the city of Bridgeport, county of Fairfield, and State of Connecticut, have invented certain new and useful Improvements in Turntables for Phonographs, of which the following, taken in connection with the accompanying drawings, is a specification.

This invention relates to improvements in turn-tables for phonographs, and has for an object to provide a turn-table which may be made from sheet metal, and which may be conveniently pressed to shape and formed by a minimum of simple manufacturing operations.

Another object is to provide a turn-table, which will possess the combined characteristics of lightness, strength, and rigidity, and in which all tendency to warp or bend, due to strains, atmospheric conditions, or other causes, is entirely eliminated.

Still another object is to so strengthen and reinforce the turn-table by means of ribs formed integral with the sheet metal structure, as to resist strains along all diameters and chords of the turn-table.

A further object is to provide improved means for securely attaching the fabric covering to the upper surface by efficient manufacturing methods, and to enclose the edge of the covering, so that it will be protected against wear and detachment due to rough handling. To this end, an improved form of flanged strengthening-rim is provided, which, in addition to its function of strengthening the turn-table and maintaining its flat disc-form, encloses and protects the edge of the fabric covering, as above pointed out; and, furthermore, adds great attractiveness to the turn-table.

A still further object is to prevent the transmission through the turn-table of sound generated at the record, and to eliminate all extraneous vibrations; this, in order that proper sound reproduction may obtain, without the deleterious diaphragm-effect of the turn-table.

Finally, an object is to provide an improved method of forming and constructing the turn-table, in order to produce an improved structure, and also economy in manufacture.

With these and other objects in view, embodiments of the invention are shown in the accompanying drawings; and these embodiments will be hereinafter more fully described with reference thereto, and the invention finally pointed out in claims.

In the drawings—

Fig. 1 is a plan view of a turn-table, according to one embodiment of the invention, a portion of the fabric covering being removed to clearly illustrate the body of the turn-table;

Fig. 2 is a vertical sectional view of same, taken along the irregular line 2—2 of Fig. 1;

Fig. 3 is an enlarged detail sectional view of the rim portion of the turn-table, and showing the same partially bent to shape, this being the first formative step;

Fig. 4 is a similar view, and showing the rim-flange completed, or after the final formative step;

Fig. 5 is a similar view, showing the fabric covering finally positioned within the rim-flange;

Fig. 6 is a fragmentary plan view, showing the first formative step in constructing the turn-table plate-portion;

Fig. 7 is a sectional view thereof, taken along the diameter 7—7 of Fig. 6;

Fig. 8 is a fragmentary plan view, showing the second formative step;

Fig. 9 is a sectional view thereof, taken along the irregular line 9—9 of Fig. 8;

Fig. 10 is a fragmentary plan view, showing the third formative step, in which the center-bearing, for engaging the turn-table spindle, is attached;

Fig. 11 is a sectional view thereof, taken along the irregular line 11—11 of Fig. 10;

Fig. 12 is a plan view of the completed turn-table with the fabric covering attached;

Fig. 13 is a sectional view along the line 13—13 of Fig. 1; and

Fig. 14 is a sectional view along the line 14—14 of Fig. 1.

Similar reference characters indicate corresponding parts throughout the several figures of the drawings.

Referring particularly to Figs. 1 and 2 of the drawings, the illustrative embodiment of the invention disclosed therein comprises a sheet-metal disc 20, preferably of steel having a center hole 21, and a central depressed or dished portion 22 surrounding

- the center hole in concentric relation thereto. A plurality of equi-spaced perforations, or slots is formed in the disc, these being here shown as alternating long slots 23 and 24, the metal cut to form these slots being bent downwardly at right angles along one or both of the longitudinal edges thereof, to form reinforcing ribs 25 and 26. These will hereafter be referred to as "flanged perforations." These ribs may all be formed at both longitudinal sides, as shown with relation to the long slots, or at one side only, as shown with relation to the short slots—the ribs in the latter case, of course, corresponding in depth to the entire width of the slots (Fig. 14), while in the case of the ribs at both sides of the slots, they are only half the width (Fig. 13). The long slots are arranged tangentially, with relation to a circumferential line disposed between the periphery of the depressed portion and the center hole, while the short slots are radially disposed and extend across the annular area surrounding the dished portion, all of the slots extending in close proximity to the rim-flange. The long slots are in rectangular relation to each other, their opposed inner ends overlapping, so that the slots and reinforcing ribs intersect substantially every diameter and chord of the disc at one or more points. The short radial slots are also preferably arranged at right angles to each other, as shown.
- 35 A plurality of circular perforations 27 is provided in the annular raised-portion of the turn-table in alternating relation to the slots. The perforating of the turn-table and the provision of the slots and ribs prevents the transmission of sound generated at the record, breaks up the diaphragm-effect of the turn-table, and diminishes all extraneous sounds, whether generated through the vibrations of the motor, transmitted through the turn-table shaft, or resulting from sympathetic vibration due to the natural period of the turn-table itself.
- 50 The center-bearing for engaging the turn-table spindle is secured to the under side of the dished or depressed portion 22, and consists of a casting having a flat upper-portion 28, and a tubular central portion 29 having a tapered bore, the taper being such as to fit the end of the turn-table spindle and being not greater in diameter at its reduced end, than is the center hole 21 of the turn-table.
- 60 A plurality of radially-extending, equi-spaced attachment lugs or ears 30 (Fig. 1) are provided upon, and formed integral with, the flat upper portion 28, and are secured to the turn-table by means of rivets 31, countersunk at their upper ends, as clearly indicated in Fig. 2. The lugs 30 are so designed as to extend within the spaces

between the ends of the slots 23, and serve to increase the rigidity and strength of the turn-table structure, by providing a substantially-continuous reinforcement from the center outward.

70 The strengthening of the turn-table is further enhanced by the formation at its outer periphery of a beaded circumferential rib 32, formed by bending the material downwardly at right angles to the surface of the turn-table, as at 33 (Figs. 2 and 3), and then upwardly and inwardly in a continuous curl, as at 34,—the inwardly-directed edge portion being spaced from the portion 33, so as to provide a restricted slot through which the edge of the fabric covering, presently more fully referred to, may be inserted.

75 As shown in Fig. 3, the rib is first formed into a U shape by a simple stamping operation; and it is then bent into its final bead form, as shown in Figs. 4 and 5, by a second stamping operation, the upper surface of the rib being preferably slightly below the upper surface of the turn-table, so that the fabric covering will project substantially above this uncovered rib.

80 The covering for the turn-table consists of an upper layer 35 of a suitable fabric—velour, felt, or the like—and an under-layer 95 of paper shellaced on both sides, and secured by the shellac to the fabric and the upper surface of the turn-table, and furnishing a binder therebetween. At its marginal portion, the covering is inserted into the tubular rib, as shown in Fig. 5, and is thereby enclosed and protected against wear and the possibility of detachment through rough handling. The edge of the rib, being directed inwardly so as to face the downwardly-extending marginal-portion of the covering, is thereby concealed so that a continuously rounded surface, entirely free of sharp edges, is provided.

90 Figs. 6 to 12 illustrate the method of forming the turn-table, according to the invention. A circular blank of sheet steel, or other suitable material, is provided, and in one operation, the rim-flange is pressed into U-form, as at 37; cuts 38 to form the slots are provided; and the central and annular perforations 21 and 27 are produced. (See Figs. 6 and 7.)

100 The next step consists in completing the rib by curling the same inwardly, as shown enlarged in Fig. 4, flanging the cuts 38 to form the slots with their reinforcing ribs, and depressing the central dished-portion 22. (See Figs. 8 and 9.) The next step consists, as shown in Figs. 10 and 11, in attaching the center bearing for the turn-table spindle; and the final step, as shown in Fig. 12, is to attach the fabric covering.

110 With the present improvements, a turn-table is provided which may be produced

economically and with simple manufacturing operations, and which will possess the characteristics of strength, lightness, and yet be rigid enough to maintain its flat disc-form under practically all conditions.

There is illustrated and described a preferred and satisfactory embodiment of the structure and method comprising this invention, but it is obvious that certain of the novel features may be used alone or in conjunction with one or more of the other features; and that other changes may be made therein within the spirit and scope of the invention, as defined in the appended claims.

Having now described the invention, what is claimed as new, and for which Letters Patent is desired, is:

1. A turn-table for phonographs, comprising a sheet-metal disc having a plurality of perforations therein, to break up the diaphragm-effect of the turn-table.

2. A turn-table for phonographs having a plurality of flanged perforations.

3. A turn-table for phonographs, comprising a sheet-metal disc having a plurality of slots extending outwardly from the center.

4. A turn-table plate for phonographs, consisting of a disc of sheet-metal having its outer edge formed into a reinforcing rib, and its surface provided with openings to break-up the diaphragm-effect of the portion confined by the rib, the edges of the disc at the openings being reinforced to give the disc rigidity.

5. A turn-table for phonographs having a plurality of perforations extending in a direction outwardly from the center, and hav-

ing downwardly extending flanges along 40 their edges.

6. A turn-table for phonographs, comprising a sheet-metal disc having a plurality of slots formed therein, and strengthening flanges, extending downwardly from the 45 edges of said slots, the strengthening flanges being formed of metal displaced in making the slots.

7. A turn-table for phonographs, comprising a sheet-metal disc having a plurality of 50 radial slots formed therein, and flanges bent downwardly from their longitudinal edges.

8. A turn-table for phonographs, having a plurality of strengthening ribs disposed in intersecting relation with substantially every 55 diameter of the disc.

9. A turn-table for phonographs, having a plurality of elongated slots formed therein, and having flanges extending along their longitudinal sides, and reinforcing the disc 60 along substantially every diameter thereof.

10. A turn-table for phonographs, comprising a sheet-metal disc, a plurality of spaced reinforcing ribs, and a center bearing 65 for the turn-table spindle secured to the disc, and having radial projecting portions extending into the spaces between the ribs.

11. A phonograph turn-table disc of sheet material having a plurality of perforations to break up the diaphragm-effect of the turn-table, the perforations being disposed in intersecting relation to substantially every 70 diameter of the disc.

Signed at Bridgeport, in the county of Fairfield, and State of Connecticut, this 16th 75 day of December, A. D. 1921.

RAY B. WHITMAN.
